UNITED STATES PATENT OFFICE.

HENRY FRANK, OF NEW YORK, N. Y.

GAME-BOARD.

SPECIFICATION forming part of Letters Patent No. 734,313, dated July 21, 1903.

Application filed September 13, 1902. Serial No. 123,314. (No model.)

To all whom it may concern:

Be it known that I, HENRY FRANK, a citizen of the United States, and a resident of the city of New York, Glendale station, borough 5 of Queens, in the county of Queens and State of New York, have invented a new and Improved Game-Board, of which the following is a full, clear, and exact description.

This invention relates to improvements in 10 game-boards particularly adapted for the mechanical playing of the game of base-ball, the object being to provide a board so arranged that the rolling ball employed will indicate the various plays, that may be recorded in 15 the usual manner, thus making the game interesting, and in the playing of it considerable skill may be acquired.

I will describe a game-board embodying my invention and then point out the novel features in the appended claims.

Reference is to be had to the accompanying drawings, forming a part of this specification, in which similar characters of reference indicate corresponding parts in both figures.

Figure 1 is a plan view of a game-board embodying my invention, and Fig. 2 is a longitudinal section thereof.

Referring to the drawings, 1 designates the board, which may be of any desired size, and 20 in use it is designed to be held in an inclined position. Therefore I provide it at its upper end with legs 2, which may be hinged to the under side of the board. The board has an upwardly-extended flange 3 extended along 25 its sides and ends, and at one side is a race-way 4, through which a ball is designed to be forced by means of a plunger 5 at the lower end of the raceway. This plunger 5 has a finger-piece 6, extended through a slot in the 30 top plate 7, and it is impelled forward by means of a spring 8.

At the upper end of the board is a curved deflecting bar or plate 10, and arranged below this deflector 10 is a series of blocks or 45 uprights 11, 12, and 13. At the upper sides of the blocks are pins 14, which form the side walls of pockets for receiving the ball, and on the blocks at each pocket is printed the play. There is a space 15 between the end 50 of the block 11 and the side of the board, through which the ball may pass as it is discharged from the raceway. There is also a

space 16 between the blocks 11 and 12, a space 17 between the blocks 12 and 13, and a space 18 between the end of the block 13 and the 55 adjacent side or flange of the board. It will be noted that the block 11 has four pockets, the block 12 two pockets, and the block 13 three pockets.

Arranged in the field is a diamond 19, having a home-plate 20, a pitcher's box 21, bases 22 23 24, and a short-stop position 25. Arranged adjacent to these several positions in the diamond are receiving devices for the ball. As here shown, these receiving devices 65 consist of pockets formed of upwardly-extended curved plates 26. The basemen, a pitcher, and short-stop will be indicated by pins 27 rearward of the receiving devices. It will be noted that the block 12 is in direct 70 line back of the batter's position on the diamond, thus serving as a back-stop.

In the outfield are receiving devices 28, similar to the first-named receiving devices, and the fielders are indicated by the pins 29. 75

At the lower end of the board is a series of pockets, the side walls of which are formed by forwardly-extended pins 30, and on the block or strip in which the pins extend is printed matter indicating certain plays. 80

Arranged variously in the field of the board are deflecting or obstructing devices consisting of pins 31, extended upward from the board.

In playing the game the general rules of 85 base-ball will be practically followed out. Briefly, the operation, however, may be stated as follows: Sides will be chosen—that is, two persons will take choice as to which shall have the first inning. The ball 32 is to be 90 placed in the runway when the plunger 5 is in its lowermost position. Then by releasing the plunger the spring will force it forward, consequently forcing the ball through the runway against the deflector 10. Should the 95 ball pass through either one of the openings 16 or 17, it will be counted as a hit; but should it pass in its movements around the field into any one of the receiving devices the striker will be counted out. Should the ball 100 pass through the opening 18, it will be regarded as a foul ball. Should it stop in the center pocket of the block 13, it will be considered as a ball, and such pockets are also

formed in the block 11. Other plays will be indicated by the printed matter on the blocks, as before indicated.

As the printed matter clearly indicates the 5 plays, it is thought further description is unnecessary, especially as the rules of the game will be attached to the board.

Having thus described my invention, I claim as new and desire to secure by Letters 10 Patent—

1. In combination with means for impelling a rolling device, of a game-board having a diamond and players' positions indicated thereon, a series of uprights extended across 15 the board above the diamond and spaced apart, the said uprights being provided with pockets, the center one of the uprights being in line with and back of the batter's position on the diamond, substantially as specified.
2. In combination with means for impelling a rolling device, a game-board having a 20 runway at one side in which the impelling

means is arranged, a series of uprights in alinement transversely of the board at the upper portion and spaced apart, the outer uprights being spaced from the sides of the board, each of said uprights having a plurality of pockets, one of the outer uprights having a less number of pockets than the other outer upright, and the center upright having 25 a less number of pockets than either of the others, the said center upright being in line with and directly back of the home-plate, a series of pockets at the lower end of the board, uprights placed at players' positions 30 on the board, and pins variously arranged on the board, substantially as specified.

In testimony whereof I have signed my name to this specification in the presence of two subscribing witnesses.

HENRY FRANK.
